UNITED STATES PATENT OFFICE.

SAMUEL J. DANTZIC, OF WASHINGTON, DISTRICT OF COLUMBIA.

DRESS ATTACHMENT.

Application filed October 26, 1923. Serial No. 670,863.

To all whom it may concern:

Be it known that I, SAMUEL JOSEPH DANTZIC, a citizen of the United States, residing at the city of Washington, in the 5 District of Columbia, have invented certain new and useful Improvements in Dress Attachments, of which the following is a specification.

This invention relates to improvements in 10 ladies' dress attachments and more particularly adapted to be used on ladies' dresses or skirts as shown in the accompanying drawings.

An object of this invention is to provide 15 a stiffener which is attachable to a skirt at a point where the skirt spans the interstice between the buttocks to prevent adherence of the skirt in the interstice when the wearer arises from a sitting to a standing position.

20 A further object of this invention is to provide an attachment of this character which is readily attachable to and detachable from the dress, skirt or the like and so constructed to be comfortable to wear.

25 Referring now to the drawings forming part of this specification:—

Figure I is a sectional view of a skirt illustrating the application of this invention.

30 Figure II is an elevational view of the same.

Figure III is a plan view of the fastener comprising part of the present invention.

Figure IV is an elevational view of same.

35 Figure V is a plan view of the stiffening strip which forms a part of the present invention.

Figure VI is an elevational view of a slightly modified form of a stiffening strip 40 illustrating its application, and

Figure VII is a similar view of another modified form of stiffening strip.

Referring to the drawings in which like 45 designating characters distinguish like parts throughout the several parts.

In order to illustrate the application of the present invention a skirt 1 is shown which may be of the usual design. Mounted upon the skirt approximately mid-way the 50 ends thereof is a stiffening strip 2 which may be made of celluloid, mohair or other suitable material. The strip may be applied

to skirt in any desired manner, in the present instance it is shown detachably secured thereto by clasps as well as sewed to skirt 55 as will be more fully hereinafter described. It is sufficient that stiffening strip comprise a relatively small oblong body as shown in body although the contour may be changed as desired.

60 If it is desired to use a stiffening strip in accordance with this invention which is detachably engaged to the skirt by a clasp, the form of clasp shown in Figures III, IV, and V, may be shown to advantage. This 65 form of clasp consists of a circular plate 3, having openings therein, each provided with an outwardly pressed annulus 4. These plates may be sewed or otherwise secured to the inner face of the skirt at the rear of 70 the latter, and are provided with aligning openings 5 which are adapted to receive resilient clips or fingers 6 carried by the strip 2. Each clip consists of a strand of wire 75 bent upon itself having the inner end thereof secured in any desired manner to one end of the strip while the opposite end extends beyond the strip and is compressible so as to be engaged through its corresponding openings 5 in the annulus 4. It will be 80 noted that the outer ends of the clips are of substantially diamond shape configuration when compressed so that the clips must be manipulated in an especial manner in order to engage same through the opening 5 as 85 illustrated in Figure III of the drawings.

If desired the strip 2 may be sprung into pockets 7 carried on the inner face of the skirt or sewed to the skirt as shown in Figure VII, of the drawings, the strip 2 being 90 provided with perforations 8.

In this invention a very advantageous and simple attachment is thus provided, slight changes may be made without departing from the spirit of the invention and within 95 the scope of the claim hereto appended.

What is claimed is:—

In combination with a skirt, an attachment including a stiffening strip to span the interstice between the buttocks and secured 100 to the garment at a point where the latter spans the buttocks.

SAMUEL J. DANTZIC.
